COMBINED SLINGSHOT AND ARROW CATAPELTT

Filed April 2, 1947

Donald Bean
Inventor

Leslie M. Hansen

His Attorney

1. The device of claim 1, in which the lower portions of the arms are each provided with a slot for receiving a binding post, the binding post being rotatable relative to the lower portions of the arms.

2. The device of claim 1, in which the lower portions of the arms are each provided with a slot for receiving a binding post, the binding post being rotatable relative to the lower portions of the arms.

UNITED STATES PATENT OFFICE

2,610,620

COMBINED SLINGSHOT AND ARROW CATAULPT

Donald Bean, San Jose, Calif.
Application April 2, 1947, Serial No. 738,866

4 Claims.

(Cl. 124—20) **1.** A combined slingshot and arrow catapult device, comprising a pair of arms, each having a head portion, a shank portion and a lower portion, the lower portions being rotatable relative to the head portions, the shank portions being rotatable relative to the lower portions, the lower portions being each provided with a slot for receiving a binding post, the binding post being rotatable relative to the lower portions.

This invention relates to missile projectors and more particularly to an improved missile projector adapted to be readily and quickly converted from an arrow catapult to a slingshot and vice versa.

It is one object of the present invention to provide a convertible missile projector of simplified construction which can be manufactured economically and yet be highly efficient and effective in use.

Another object is to provide a combined slingshot and arrow catapult requiring a minimum number of parts so related as to be readily positioned with respect to each other for either one or the other of its positions of use and to be of such compactness when in one of its positions of use as to be pocket size for the convenience of the user.

Another object is to provide an arrow catapult by arranging the normally diverging arms of a slingshot crotch in abutting relation.

Another object is to provide a pair of slingshot crotch arms so configured as to form an arrow guide when the arms are in abutting relation.

Another object is to provide interlocking crotch arms for a slingshot cooperating with each other when in abutting relation to present an arrow guide in alignment with the anchorage of the elastic sling associated therewith.

Other objects and advantages will become apparent from the following description in connection with the accompanying drawings in which:

Fig. 1 is a perspective view of my improved missile projector illustrating the same as a slingshot.

Fig. 2 is a side elevation of the crotch arms shown in Fig. 1.

Fig. 3 is an elevational view of the crotch arms of Fig. 2 disposed 90° relative to the same, the arms also being shown in dotted lines to illustrate transition thereof during conversion into an arrow catapult.

Fig. 4 is a fragmentary elevation of the arms during transition as shown in dotted lines in Fig. 3 and taken along line 4—4 thereof, certain portions of the arms being broken away for purposes of illustration.

Fig. 5 is an elevation, complementary to Fig. 3, showing the crotch arms in abutting relation for use as an arrow catapult.

Fig. 6 is a perspective view of the missile projector illustrating the same as an arrow catapult.

The device comprises a pair of arms 10 and 10' pivotally connected with respect to each other at 11 and adapted to provide a crotch 12 for a sling-

15 20 25 30 35 40 45 50 55 60 65 70 75 80 85 90 95

2. The arms 10 and 10' are preferably of identical shape each comprising a head portion 14—14', a shank portion 15—15' and a lower portion 16—16', respectively.

The head portion 14—14', of each arm is provided adjacent one edge thereof with a binding post 18—18', respectively, in substantial alignment with the lower portion 16—16' thereof. The head portions 14—14' are provided, adjacent the opposite edges thereof, with a hump portion 19—19' terminating in an indentation 20—20' disposed substantially midway of the upper and lower ends of the binding post 18—18', i. e., in a plane extending laterally therefrom. Adjacent the indentation 20—20' each head portion is provided with a flat surface 21—21' lying in a plane extending radially from the pivotal connection 11 of the arms.

It will be understood by those skilled in the art that the pivotal connection between the arms 10 and 10' may be provided by a simple pin or by any well known form of interlocking appendages on the arms 10 and 10'.

In the present disclosure the lower portion 16—16' of each arm is reduced to about one half the thickness of the arm 10—10' itself so that when the lower portions 16—16' lie side by side, the remaining portions 14, 15 and 14', 15' of the arms 10 and 10', respectively, will be disposed in substantially the same plane with respect to each other, Fig. 2. Consequently, the arms 10—10' are rotatable relative to each other in a common plane and, providing the extreme ends of the lower portions 16 and 16' are in proximity to the pivotal connection 11 therebetween, as for example the broken ends thereof illustrated in Figs. 3 and 5, the two arms are adapted to be relatively swung from the position as shown in Fig. 3 to the position shown in Fig. 5.

It will be noted that the cut back in thickness of the arm 10—10' is such as to provide a pair of faces 22—22' and 23—23' disposed at an obtuse angle with respect to each other on the shank side of the pivotal connection 11 between the arms 10 and 10'.

The face 22 of the arm 10 is disposed to abut one side 24' of the base of the shank 15' of the arm 10' and the face 22' of the latter is disposed to abut the other side 24 of the base of the shank 15 of the arm 10 for limiting relative swinging movement of the binding post edges of the two arms toward each other, Fig. 3. The faces 23

and 23' of the two arms are so disposed as to permit the indented edges 20-20' of the two arms to swing toward each other until the respective flat surfaces 21 and 21' thereof abut each other as is shown in Fig. 5.

From the foregoing it will be apparent that when the arms 10-10' are swung in one direction relative to each other they are free to engage each other along their respective flat faces 21-21'. In this position, the adjacent indentations 20-20' on the head portions of the arms cooperate with each other to form an arrow guide 40 between the binding posts 18-18'. However, when the arms 10-10' are swung away from the aforementioned position in which their flat surfaces 21-21' engage one another, a total of more than 180°, the faces 22-24 and 22'-24' on the respective arms cooperate with the pivotal connection 11 therebetween to limit further movement of the arms toward each other. Consequently, despite the arms being pressed toward each other by the hand of the person holding the arms, see Fig. 1, the arms are maintained at an acute angle relative to each other in the form of a slingshot crotch.

It is apparent that when the lower portions 16 and 16' of the two arms are extended substantially beyond the pivotal connection 11 between the arms, the foregoing relative swinging movement of the arms between the position shown in Fig. 3 to that of Fig. 5 can only be accomplished when the two arms are spaced relative to each other. In other words, the two arms 10 and 10' must first be shifted laterally along the axis of the pivotal connection 11 and with respect to each other so that the extensions of the portions 16 and 16' can pass the faces 23 and 23', respectively of the opposing arm.

While the foregoing manipulation of the arms can be easily accomplished when a simple pin provides pivotal connection between the arms 10 and 10' I prefer to use telescoping pins 30 and 31 as disclosed in Fig. 4. Moreover, these pins 30 and 31 are hollowed to receive a tension spring 32 having its ends secured to the cap portions 33 and 34 of the pins 30 and 31, respectively. The arrangement is such as to permit lateral sliding movement of the pins 30 and 31 relative to each other when the two arms are manually separated, Fig. 4, into a position allowing their lower portions to swing past the shank portion of the opposing arm whereupon the spring 32 promptly returns the two lower portions 16 and 16' into abutting relation with respect to each other.

A resilient member such as a rubber band 35, or the like, provided with a medial pocket 36 and having opposite ends 37 and 38 suitably secured in any well known manner to the binding post 18 and 18' respectively, completes the missile projector of the present invention. This elastic band 35 is readily inverted upon interchange of the pivoted arms 10 and 10' from one to the other of their positions of use as will now be explained.

When the device is arranged as is shown in Figs. 5 and 6 for the purpose of shooting an arrow 39 at an object, such as game, it will be noted that the indentations 20 and 20' cooperate with each other to provide an arrow guide 40. This arrow guide is disposed in a plane p substantially aligned with the binding posts 18 and 18' and the elastic band 35 when it is stretched perpendicular with respect to the arms 10 and 10'. The shaft of the arrow 39 can therefore lie

in the line of sight between the butt end 41 of the arrow and the object to be hit. Consequently when the pocket 36 is released the arrow is thrust forward along the line of sight and will be projected, without deviation, toward the object aimed at.

Should the hunter's store of arrows be exhausted and the game, although sighted, not yet killed, the hunter can quickly convert the missile projector into a slingshot by swinging the arms inversely from the position shown in Fig. 5 to that of Fig. 3. The rubber band 35 is then inverted or twisted into a condition to extend straight from the binding posts 18-18'. The hunter can now continue shooting by picking up stones or pebbles which are of a size capable of being shot from the pocket 36. Then too, as the hunter advances toward the game and recovers arrows which he had previously projected, he can quickly reconver the device back into an arrow catapult for more effective shots at the game.

The device can be easily carried in one's pocket when positioned as an arrow catapult and can be employed at sporting events for demonstrations of skill. It is inexpensive, easily cared for or stored and provides an all-round implement for sportsmen of the field.

While I have specifically described one form of my new missile projector, it will be apparent that the same is capable of various modifications and alterations without departing from the spirit of my invention. I therefore desire to avail myself of all modifications and alterations coming within the purview of the appended claims.

What I claim as new and desire to protect by Letters Patent is:

1. A missile projector comprising a pair of arms pivotally connected adjacent one end thereof for swinging movement in either direction, means on the opposite end of each arm providing an anchorage for an elastic sling, means at said one end of each of said arms adapted to abut each other and to cooperate with said pivotal connection for limiting movement of said arms in one direction under the influence of one hand of a person gripping said arms so as to provide a slingshot crotch, and a head portion on the opposite end of each arm laterally adjacent the anchorages thereof adapted to abut each other when said arms are swung in an opposite direction, each said head portion having a recess formed thereon in a plane substantially laterally of said anchorages for providing an arrow support between said anchorages.

2. A missile projector comprising a pair of arms each having a shank portion and a head portion provided with a binding post and a hump portion extending laterally of and adjacent said binding post, means pivotally connecting said arms together adjacent one extremity of the shank portion opposite the head portion thereof, an elastic sling suspended from said binding posts, a shoulder at said one extremity of each of said shank portions adapted to abut each other upon movement of said arms in one direction under the influence of the grip of one hand of a person using the device, said abutting means cooperating with said means for pivotally connecting said arms for limiting swinging of said arms in said one direction beyond a crotch formation when gripped by the hand of a person as aforesaid, said arms being free to move in an opposite direction until the laterally extending hump portions of the head portions

thereof engage each other, said hump portions on said arms terminating in indentations cooperating to provide an arrow guide in a plane transversely between said binding posts.

3. A missile projector comprising a pair of arms each having an offset binding post at one of its ends to which is secured the end of an expansible sling and each having a shank portion provided with a narrower portion adapted to pivotally overlie the narrower portion of the opposing arm, means connecting said arms together for pivotal movement about an axis extending through the narrower portions thereof, said shank portions each having faces thereon adjacent said narrower portions and said connecting means adapted to engage one another for limiting pivotal movement of said arms in one direction by the grasping action of the hand of a person using the device to thereby dispose the arms in diverging disposition with respect to each other, said arms being free to swing in an opposite direction for abutting relation with respect to each other with said arms substantially parallel, and a head portion on the abutting sides of each of said arms in the region thereof laterally spaced from the offset binding posts thereof, said head portions terminating adjacent their abutting sides in indentations cooperating with each other to provide an arrow guide between said binding posts.

4. A missile projector comprising a pair of arms pivotally connected together adjacent their one ends and having an expansible sling secured

to their opposing ends, said arms being interlocked in the region of their pivotal connection with each other for swinging movement in either direction in a common plane, means adjacent the pivotal connection of each of said arms adapted to abut each other for limiting swinging movement of said arms in one direction beyond a position in which said arms are disposed at an acute angle relative to each other in the form of a V crotch, means for yieldably holding said arms in interlocked relation in such a manner that the arms are separable sufficiently for swinging movement in an opposite direction into substantially parallel relationship with respect to each other, and a head portion on each of said arms laterally of the ends thereof to which said expansible sling is secured, said head portions being provided with humps terminating in indentations cooperating to provide an arrow guide when said arms are disposed in parallel relationship with respect to each other.
